York, N. Y., a corporation of New York

Application May 22, 1947, Serial No. 749,813

8 Claims. (Cl. 91—45)

1

This invention relates to an apparatus for automatically spraying parts and more particularly to an apparatus for oil spraying step by step banks arranged in multiple on telephone equipment.

It is an object of the present invention to provide a simple and effective apparatus for automatically spraying parts.

In one embodiment of the invention, wherein the banks of the multiple are arranged in a row with the wiper ends of the terminals extending upwardly and the banks are individually mounted on pairs of supporting pins extending horizontally from a fixture, the fixture is placed on a conveyor which moves the banks successively under an oil spraying head. The oil spraying head, in the form of an air-operated spray gun, is mounted for vertical reciprocation by a fluid-actuated plunger under control of an electrical control mechanism including a pair of normally open switches connected in series. The switches, as the bank multiple is advanced, will both be simultaneously closed by the pins carrying one bank when the bank is properly positioned under the head, thereby completing a circuit to cause the head to be lowered into close proximity to the bank and cause the spray gun to be momentarily actuated to spray a predetermined amount of oil, in the form of a mist, onto the wiper ends of the terminals of the bank, after which the head is rapidly moved to its raised position.

The invention will be more fully understood from the following description when considered in conjunction with the accompanying drawings illustrating a preferred embodiment thereof in which

Fig. 1 is a fragmentary front elevational view of the oiling apparatus with parts broken away and showing the oil spraying head in raised position;

Fig. 2 is a vertical sectional view of the apparatus shown in Fig. 1 and taken on the line 2—2 thereof;

Fig. 3 is a vertical sectional view of a portion of the apparatus taken on the line 3—3 of Fig. 2 and showing the head lowered to an operative position adjacent a bank of the bank multiple; and

Fig. 4 is a diagrammatic view illustrating the spray head and the oil and air connections thereto and the electrical control system for controlling the operation thereof.

In the embodiment of the invention illustrated in the drawings, the oiling apparatus is designed to apply a spray of oil in the form of a fine mist 55 head due to the action of gravity when pressure

2

on the upwardly extending wiper ends of the terminals 10 of the individual banks 12 of a bank multiple forming part of step by step telephone equipment. As indicated in Fig. 2, the bank multiple may be double and arranged side by side, as indicated at 14 and 15. A pair of banks 12, one from each of the bank multiples 14 and 15, as shown in Figs. 1 and 2, are mounted on a pair of supporting rods 17—17, which are inserted into apertures in and extend horizontally outwardly from a vertical panel 18 which may form a part of a piece of telephone equipment or a supporting fixture 20. The banks 12 are retained on the rods 17 by shoulder portions 22 formed thereon and are arranged end to end in spaced relation to each other in a horizontal row, as indicated in Figs. 1 and 3. The supporting fixture 20 is placed on a belt conveyor 24, supported on a table 25, for moving the fixture 20 at a relatively slow speed along a predetermined path between guide rails 27 and 28. The return course 29 of the belt 24 is supported in a housing 30 mounted on the under side of the table 25.

The banks 12, as they are carried along by the conveyor belt 24, are moved underneath an oil spraying head 32 comprising a pair of spray guns 33 and 34 mounted in vertical alignment above the path of travel of the bank multiples 14 and 15, respectively. The head 32 is mounted on the end portion of a horizontal arm 36 secured to and extending forwardly from a vertically movable shaft or rod 38 mounted for vertical reciprocation in a guide member 39 secured to the table 25 (Fig. 2). The rod 38, at its lower end, is attached to and forms an extension of a piston rod 40 operatively connected to a piston 41 (Fig. 4) mounted in a cylinder 42, which forms a fluid actuator for reciprocating the head 32. The cylinder 41 has an enlarged head or plate 44 (Fig. 1), to which are secured one end of each of a pair of vertically extending rods 45—45, the other ends of which are secured to the table 25 to rigidly secure the cylinder 42 to the table 25. Fixed to the lower end of the rod 38 is a cross head or member 47 apertured to slidably engage rods 45, which serve to prevent rotary movement of the rod 38 and the head 32. From the ends of the cross head 47 depend a pair of spring supporting arms 48—48, to the lower end of each of which is attached one end of a contractile spring 50, the other end of which is secured to the under side of the table 25. The springs 50—50 serve to maintain the head 32 in its raised position and prevent the gradual lowering of the

is not applied to the fluid actuator to maintain the piston 41 in its raised position.

Each of the spray guns 33 and 34 is positioned to direct a spray of oil downwardly and has a sheet metal tubular hood or housing 51-51 enclosing the lower end thereof. The housings 51-51 are attached to the arm 36 by a bracket 52 and have extensions 53-53 of flexible material secured to the lower end thereof. The extensions 53 are curved at their lower ends to fit the banks 12 when the head 32 is in its lowered position and serve to confine the oil spray to each of the banks 12 with which it is associated during the spraying operation. A tapered trough 54 is located directly below the head 32 and is connected, through an outlet connection 55, to an exhaust system (not shown) whereby the excess oil from the spray gun may be disposed of.

The spray guns 33 and 34 are each connected by a flexible conduit 56 to an oil supply under air pressure and by a flexible conduit 58 to a compressed air line 59, the compressed air of which is admitted, under control of a solenoid-actuated valve 60, to the spray guns to effect their operation. The spray head 32 is adapted to be moved downwardly rapidly into alignment with and in close proximity to the banks 12 and to be raised rapidly to its original starting position. During the lower portion of the downward movement of the spray head 32, the solenoid valve 60 is adapted to be energized for a predetermined interval of time to cause each spray gun to direct a predetermined amount of oil downwardly therefrom in the form of a mist onto the banks immediately below the spray head to oil the wiper ends of the contacts thereon.

The reciprocation of the spray head 32 and the operation of the spray guns 33 and 34 in proper timed relation to the movement of the banks 12 is controlled by an electrical control circuit including a pair of microswitches 62 and 63. The switches 62 and 63 are secured in a suitable rectangular framework or bracket 65, which, in turn, rests on and is secured to a plate 66 supported on a pair of vertical frame members 67-67 secured to and extending outwardly from the supporting table 25. Switch operating arms 70 and 71 of the microswitches 62 and 63, respectively, engage depending arms 72 and 73 of a pair of bell cranks 74 and 75, which are mounted for rocking movement on pivots 76 and 77 of the frame member 65. The bell cranks 74 and 75 are located adjacent the path of travel of the bank multiples and with laterally extending portions of the arms 78 and 79 of the bell cranks extending in the path of movement of the circular shoulders 22 on the supporting rod 17. The bell cranks 74 and 75 are positioned relative to each other and to the oiling head 32 so as to be simultaneously actuated by the shoulders 22 of the supporting rods 17 of an individual bank 12 when the bank is in a predetermined aligned relation to the oiling head 32 to effect the closing of the switches 62 and 63 and initiate a cycle of operation of the apparatus. The rods 17 are arranged on the panel 18 with a lesser distance between adjacent rods which support adjacent banks than between rods which support the same bank, whereby the switches 62 and 63 will be simultaneously actuated only by the rods 17 which support a bank between them.

The single pole of the switch 62 is connected to the line 82 of the power lines 82-83 and normally engages the contact 84 and is disengaged from the contact 85, respectively, of the switch

63. The single pole of the microswitch 63 is normally disengaged from the contact 86 thereof and is connected to the contact 85 of the microswitch 62. The contact 84 of the switch 62 is connected to one end of the coil 87 of a relay 88, the other end of which coil is connected to the power line 83. With the switches 62 and 63 in their normal positions shown in Fig. 4, a circuit is completed through switch 62 and the coil 87 to actuate the relay 88 and thereby close circuits across two pairs of contacts 90-91 and 92-93 of the relay. The contact 91 is connected to one end of the relay coil 87 and the contact 90 is connected, through a normally closed switch 95, to the power line 82. The circuit through switch 95 and contacts 90 and 91 comprises a holding circuit for locking the relay in operative position until switch 95 is opened. The contact 92 is connected to the contact 86 of switch 63 and the contact 93 is connected to one end of a coil 96 of a relay 97, the other end of the coil 96 being connected to the line 83. The relay 97 is adapted to actuate a pair of switches 100 and 101, which, when closed, serve to connect a coil 102 of a solenoid actuated valve 104 with the power lines 82 and 83. The relay 97 is actuated when the switches 62 and 63 are simultaneously actuated by a pair of rods 17, on which a bank 12 is supported.

The coil 102, when energized, actuates the fluid control valve 104 in one direction for directing the flow of fluid through suitable conduits and a flow control valve 106 to the upper end of the cylinder 42 to cause the piston 41 and the head 32 connected thereto to move downwardly. When the solenoid coil 102 is deenergized, the valve 104 is spring-returned to its other position to direct the flow of fluid through suitable conduits and a flow control valve 108 into the lower end of the cylinder 42 to cause the piston 41 and the head 32 to be moved upwardly to their raised position. A coil 109 of the solenoid operated valve 60 in the air line of the spray guns is connected in series with a normally open switch 110 and the coil 109 and the switch 110 are connected in parallel with the solenoid coil 102. The switch 110 (Fig. 1) is mounted in a predetermined position on the head 44 of the cylinder 42 and is adapted to be closed by engagement therewith of a cam member 114 adjustably mounted on the cross head 41 for movement therewith. After the switch 110 has been closed, it is maintained in closed position by the member 114 during the latter part of the downward movement of the piston 41 to maintain a coil 109 of the solenoid-actuated valve 60 energized to operate the spray guns 33 and 34 for a predetermined interval. The operation of the spray guns 33 and 34 is terminated after a predetermined interval by the deenergization of the coil 109, which is effected when the switch 95 is opened by engagement therewith of a member 116 mounted on the cross head 41. The switch 95 is opened to break the holding circuit to the relay 88 when the spray head 32 and the piston 41 reach their lowermost positions and, upon release of the relay 88, the coils 96, 102 and 109 are deenergized to allow the relay 87 and the valves 104 and 60 associated therewith to return to their normal positions. The valve 104, in returning to its normal position, causes the reversal of fluid pressure in the cylinder 42 to effect the upward movement of the piston 41 to its elevated position.

It will be noted that by adjusting the cam member 114, the point in the downward travel

of the piston 41 at which the switch 110 is closed to initiate the operation of the spray guns may be advanced or retarded to vary the interval of time during which the spray guns 33 and 34 operate.

In the operation of the apparatus, the fixture 20, with the bank multiples 14 and 15 attached thereto, is moved along a straight path by the conveyor 24 toward the oiling apparatus. With the apparatus in its normal non-operating condition, the switches 62 and 63 of the control mechanism are in their normal positions, as illustrated in Fig. 4, in which position of the switch 62 a circuit is completed therethrough and through the coil 87 of the relay 88 to hold the relay 88 in actuated position, in which position of the relay 88 the holding circuit is completed thereto through the contacts 90 and 91, and the coil 96 of the relay 97 is connected through the contacts 93-92 to the contact 86 of the switch 63. When a bank is moving into and out of position under the spray head, the switches 62 and 63 will be operated separately, but relay 97 will not be operated since the circuit thereto can only be completed by the simultaneous operation of switches 62 and 63. As the first set of banks 12 arrives at a predetermined position with respect to the head 32, the enlargements 22 on the supporting rods 17 of the first banks simultaneously engage the arms 78 and 79 of the bell cranks 74 and 75, respectively, and rock the bell cranks, the arms 72 and 73 of which, in turn, rock the levers 70 and 71 to actuate the microswitches 62 and 63. The poles of the switches 62 and 63 are thus moved into engagement with the contacts 85 and 86 and close a circuit through the switches 62 and 63 to actuate the relay 97 which, in turn, completes the circuit to the coil 102 to actuate valve 104 to its other operating position. Upon actuation to its other operating position, the valve 104 directs the fluid pressure into the upper end of the cylinder 42 to cause the downward movement of the piston 41 and the corresponding lowering of the head 32. The head 32 moves downwardly toward the set of banks thereunder, with the hoods 53-53 located immediately above and adjacent the individual banks 12 during the lowermost portion of the downward movement thereof. At a predetermined point during the latter part of the downward movement of the head 32, the switch 110 is closed by the movement of the member 114 to actuate the solenoid valve 60 and cause the spray guns 33 and 34 to project a spray of oil downwardly onto the pair of banks immediately therebeneath.

After a predetermined relatively short interval of time, the operation of the spray guns 33 and 34 is stopped by the release of control valve 60. This is brought about by the deenergization of the coil 109 when the member 116, moving with the piston 41, as it reaches the end of its downward stroke, engages and opens the switch 95. The opening of the switch 95 breaks the relay holding circuit to release the relay 88 which, in turn, breaks the circuit to release relay 97 to effect the deenergization of the coils 102 and 109 and the restoration of the valves 104 and 60, respectively, to their normal operating position. With the valve 104 in its normal operating position, fluid will be directed into the cylinder 42 to move the piston 41 and the head 32 to their raised position, thus completing one cycle of the oil spraying operation. The enlargements 22 of the rods 17, in the meantime, will have moved out of engagement with the bell cranks 74 and 75 to per-

mit them and the switches 62 and 63 to return to their normal positions, thereby completing a circuit through switch 62 to actuate relay 88 and thus restore the control mechanism to the condition shown in Fig. 4 in readiness for another cycle of operation.

What is claimed is:

1. An apparatus for spraying articles comprising a conveyor for moving said articles in a predetermined path, a spray head, guides for guiding said head for reciprocatory movement transversely of the path of travel of said articles, an actuator operatively connected to said head for advancing said head into close proximity to the path of travel of said article and for returning said head, controls for said actuator including a switch mounted in the path of movement of said articles and actuatable by the movement of an article on said conveyor into a predetermined position of alignment relative to said head for initiating the operation of said actuator, and means operable in response to the movement of said head at a predetermined point in its travel for effecting the operation of said head to project a predetermined amount of spray onto the article in alignment therewith.
2. An apparatus for automatically spraying articles comprising a conveyor for moving said articles in a predetermined path, a spray head, guides for guiding said head for rectilinear movement transversely of the path of travel of said articles and in alignment therewith, a fluid actuator having a piston operatively connected to said head for imparting reciprocatory movement thereto, valve means normally positioned to effect movement of said piston in one direction whereby said head is moved away from said conveyor, a pair of switches mounted in the path of movement of said articles and actuatable in response to the movement of an article on said conveyor to a predetermined position relative to said spray head, an electrical control circuit for actuating said valve to a second position in response to the simultaneous actuation of said switches for effecting the reverse movement of said piston whereby said head is moved into close proximity to an article in alignment therewith, and means operable in response to a predetermined portion of the movement of said head for actuating said spray head to project a spray onto said article.
3. An apparatus for automatically spraying a plurality of articles arranged in a row on a fixture and individually supported thereon by pairs of supporting members comprising a conveyor for advancing said fixture and articles thereon in a predetermined path, a spray head mounted for reciprocation in a straight line transversely of the path of travel of said articles, an actuator for reciprocating said head, means for controlling said actuator to move said head into close proximity to the path of travel of said articles including a pair of switches so spaced and positioned as to be simultaneously actuated by the article supporting members when the article on said conveyor is in a predetermined position of alignment relative to the spray head, and means operable in response to the latter part of the movement of said head for actuating said spray head to project a spray onto said article, said means for controlling the actuator being operable to effect the return of said head upon completion of said spraying operation.
4. An apparatus for automatically spraying articles comprising a conveyor for moving said articles in a predetermined path, a spray head,

guides for guiding said head for rectilinear movement transversely of the path of travel of said articles and in alignment therewith, an actuator operatively connected to said head for imparting reciprocatory movement thereto, a controller for said actuator conditioned normally to cause the actuator to hold the head away from the conveyor, a pair of switches mounted in the path of movement of said articles and simultaneously actuatable in response to the movement of an article on said conveyor to a predetermined position relative to said spray head, an electrical circuit interconnecting said controller, said switches and a source of electrical current for governing the operation of said controller and responsive to the simultaneous actuation of said switches for effecting the reverse movement of said head whereby said head is moved into close proximity to an article in alignment therewith, a controller for said spray head, and an electrical circuit connected to said controller for said spray head, and a source of current and including switch means actuatable to a closed position in response to a predetermined portion of the movement of said head for effecting the actuation of said controller of said spray head whereby said spray head is caused to project a spray for a predetermined length of time onto an article aligned therewith.

5. An apparatus for spraying articles comprising a table having guide means thereon for guiding said articles for movement along a predetermined path, a belt conveyor mounted on said table for receiving said articles in random positions longitudinally thereof for moving said articles through said predetermined path, a spray head, means guiding said spray head for rectilinear movement transversely of the path of travel of said articles and in alignment therewith, a reciprocable actuator operatively connected to said spray head for reciprocating said head to and from operative and inoperative positions spaced from and in close proximity to said path of movement of said article, respectively, control means for controlling the reciprocation of said actuator and conditioned to normally cause the movement of said actuator and the movement of the spray head to its inoperative position, said control means including a switch disposed in the path of movement of said article and adapted to be closed by an article in a predetermined position in its travel for causing a reverse movement of said actuator and the movement of said spray head to its operative position, and means for actuating said head to cause a spray to be emitted therefrom in response to a predetermined movement of said head.

6. An apparatus for spraying articles comprising guide means for guiding articles for movement along a predetermined path, a conveyor associated with said guideway for receiving said articles in random positions longitudinally thereof and in cooperation with said guide means for moving said articles through said predetermined path, a spray head, means guiding said spray head for rectilinear movement transversely of the path of travel of said articles and in alignment therewith, a reciprocable fluid actuator operatively connected to said spray head for reciprocating said head to and from upper and lower positions, spaced from and in close proximity to said path of movement of the articles, respectively, an electrically operated valve for reversing the movement of said actuator and conditioned to normally cause the movement of said actuator

and the movement of said head to its upper position, electrical control means including a switch mounted in the path of movement of said articles and adapted to be closed by an article in a predetermined position in its travel for actuating said valve to cause a reverse movement of said actuator and the movement of said spray head to its lower position, and control means operable in response to a predetermined movement of said head to actuate said head and cause a spray to be emitted therefrom.

7. An apparatus for spraying articles comprising guide means for guiding articles for movement along a predetermined path, a belt conveyor associated with said guideway for receiving the articles in random position longitudinally thereon for moving said articles through said predetermined path, a spray head, means guiding said spray head for rectilinear movement transversely of the path of travel of said articles and in alignment therewith, a reciprocable fluid actuator operatively connected to said spray head for reciprocating said head to and from an inoperative position arranged in spaced relation to said path of movement and an operative position arranged in close proximity to said path of movement, an electrically operated valve for reversing the movement of said actuator and conditioned to normally cause the movement of said actuator and the movement of said spray head to its inoperative position, circuit means connecting said electrically operated valve to a source of electrical current and including a switch mounted in the path of movement of said articles and adapted to be closed by an article in a predetermined position on said conveyor in alignment with said spray head for effecting the actuation of said valve to cause a reverse movement of said actuator and the movement of said spray head to its operative position, a normally closed electrically operated valve connected to said spray head, circuit means connecting said normally closed valve to said source of current and including a normally open switch, means movable in timed relation to said spray head for closing said normally open switch at a predetermined point in the movement of said head to effect the actuation of said head and cause the projection of spray onto the article aligned therewith, and means operable in response to the movement of said head to its operative position to open said circuit means for disconnecting said electrically operated valves from said source of current.

8. An apparatus for spraying articles comprising a conveyor for receiving articles in random position longitudinally thereof for moving said articles through a predetermined path, a spray head, means for guiding said spray head for movement transversely of the path of movement of said articles and in alignment therewith, a fluid actuator operatively connected to said spray head for reciprocating said head to and from an inoperative position spaced from the path of travel of said articles to an operative position in close proximity to the path of travel of said articles, valve means for reversing the movement of said actuator and conditioned normally to effect the movement of said spray head to its inoperative position, control means including a member mounted in the path of travel of said articles and actuated by the movement of an article into a predetermined position on said conveyor in alignment with said spray head to effect the movement of said valve to another position.

and cause the movement of said head to its operative position, normally closed valve means associated with said spray head, and control means operable in response to a predetermined movement of the spray head to actuate said normally closed valve to cause the ejection of spray from said head onto an article aligned therewith.
